ROY L. BENTON, OF GREELEY, AND WILLIAM R. BENTON, OF SALIDA, COLORADO.

PERMUTATION-LOCK.

SPECIFICATION forming part of Letters Patent No. 735,447, dated August 4, 1903.

Application filed May 12, 1903. Serial No. 156,769. (No model.)

To all whom it may concern:

Be it known that we, ROY L. BENTON, of Greeley, in the county of Weld, and WILLIAM R. BENTON, of Salida, in the county of Chaffee, State of Colorado, citizens of the United States, have invented a new and Improved Permutation-Lock, of which the following is a full, clear, and exact description.

The object of this invention is to provide simple novel details of construction for a permutation-lock that adapt it for reliable service to secure a door in closed adjustment, dispense with a key, and which is devoid of accessible openings, thus preventing the use of explosives for destroying the lock when it is in locked condition.

The invention consists in the novel construction and combination of parts, as is hereinafter described, and defined in the appended claims.

Reference is to be had to the accompanying drawings, forming a part of this specification, in which similar characters of reference indicate corresponding parts in all the figures.

Figure 1 is a front face view of a portion of a door having the improvement, showing details of the lock thereon. Fig. 2 is a horizontal sectional view substantially on the line 2-2 in Fig. 4. Fig. 3 is a front view of the lock having the front plate removed to expose interior mechanism shown in locked condition; and Fig. 4 is a like view, but showing the working parts in unlocked adjustment.

The casing 5 is rectangular and of dimensions that adapt it to receive the working parts of the lock, one side plate 5^a being removable to permit the introduction of said parts. At a suitable point within the casing 5, preferably near the center, a pivot-post 6 is positioned, and on said post the locking-disk 7 is loosely mounted. A central perforation is formed in the disk 7 for its rotatable engagement with the post 6, and upon the circular edge of the disk a plurality of angular teeth are formed, being arranged in two groups suitably spaced apart and the teeth in each group being evenly separated. As shown, there are three teeth 8 in each group;

but it is to be understood that there may be more teeth in each group if this is found to be advantageous.

The disk 7 is secured on the post 6 by a washer 9 and a nut 10, a like washer 9^a, mounted upon the post before the disk is placed thereon, serving to space the disk from the rear side wall of the casing 5.

As shown, a weight 11 is formed or secured on the disk 7 near its edge and opposite a group of the teeth 8, the weight causing the lower tooth of said group to contact with a projecting stop-pin 12 when the casing is disposed in a vertical plane, the weight then by gravity assuming the position shown in Fig. 3. Nearly opposite the weight 11 a notch 13 is formed in the periphery of the disk 7, and, as shown in Fig. 3, when the weight causes the lowest tooth 8 of the lower group of teeth to contact with the stop-pin 12 said notch is positioned near the upper wall of the casing 5.

A locking-bolt 14 is held to slide in a horizontal plane in a suitable opening *a*, formed in the end wall 5^b of the casing by clips 15 or similar means; and the bolt 14 is of such a length as will permit the inner end of the same to be embedded in the notch 13 when the bolt is moved inwardly, so that its outer end is flush with the outer surface of the end wall 5^b, as shown in Fig. 4.

In the upper side of the locking-bolt 14 two spaced notches *b* *c* are formed. The notch *b*, that is nearest to the end wall 5^b of the casing 5, receives the lower end of an arm 16^a, secured upon the inner portion of the shank 16, held to rock in a perforation in the front wall 5^a of said casing and is adapted for rocking movement by the knob 16^b, secured upon the end of the shank that projects through said front wall, as shown in Fig. 2. It will be seen that by manipulation of the knob 16^b the arm 16^a will be adapted to slide the locking-bolt 14 so as to project the retracted outer end of the same outside of the end wall 5^b of the casing when the parts are adjusted as shown in Fig. 4.

Between the rock-arm 16^a and the periph-

ery of the locking-disk 7 a detent-dog 17 is held to slide vertically by its engagement within the guide-box 18, within which it is loosely fitted, said guide-box projecting from the rear wall of the casing. The relative position of the detent-dog 17 adapts it to seat upon the locking-bolt 14 between the notches *b c* therein when the bolt is drawn inward, so as to unlock the bolt from a hasp of any suitable form (not shown) or from a recess *o* in the jamb of a door-casement, as shown in Fig. 2, this retraction of the bolt being permitted only when the notch 13 is located directly opposite and near the inner end of the locking-bolt.

In the casing 5, near the right-hand upper and lower corners thereof, two similar spindles 19 20 are rotatably supported, as will be hereinafter explained. Upon the portions of the spindles 19 20 that occupy the casing 5 and which are preferably angular in cross-section the elongated hubs 21^a 22^a of the two similar tumbler-disks 21 22 are mounted, having mating angular axial perforations that receive the spindles. The hubs 21^a 22^a project at each side of the tumbler-disks 21 22 and are truly cylindrical at their ends, the latter fitting loosely into sockets oppositely formed in pairs in the inner surfaces of the front and rear wall of the casing 5. The circular tumbler-disks 21 22 have spaced teeth 23 formed on their peripheries. As shown, each disk is provided with three teeth; but this number of teeth may be changed to alter the combination, it being understood that the number of teeth 8 in each group on the tumbler-disk 7 is correspondingly changed.

The portions of the spindles 19 20 that project through the front plate 5^a are of sufficient length to pass through perforations in a front plate A', forming an integral portion of a door A, wherein the lock-casing 5 is embedded and secured by any suitable means, said door having a recess or the like in its inner surface to permit the insertion of the lock therein. It is to be understood, however, that in some cases the lock may be secured upon the inner surface of the door that is not recessed.

On the ends of the spindles 19 20 which extend through the door portion A' similar knobs 19^a 20^a are mounted and secured, the inner true ends of the knobs having close contact with the level surface of the portion A', thus preventing the introduction of explosives within the door-recess or the lock-casing. On the portion A' of the door A a circular scale 24 is formed or secured around each knob 19^a 20^a, and an index-finger 25 projects from each knob to indicate on the scale to which it is adjacent.

The detent-dog 17 is provided with an offset head 17^a at the upper end on the side of said dog opposite the tumbler-disk 7. A tripping-lever 26 is pivoted, as at *e*, near one of

its ends upon the rear wall of the casing 5, so that one end of the lever may have contact with the lower side of the offset head 17^a. The longer portion of the lever 26 extends from the pivot *e* over the outer side of the locking tumbler-disk 7.

Two studs 27 28 project from the outer face of the disk 7, and preferably said studs are at an equal distance from the notch 13.

When the locking-bolt 14 is moved inwardly, so that its inner end occupies the notch 13 and the detent-dog 17 rests upon the upper side of said bolt between the notches *b c*, it will be seen that by manipulation of the knob 16^a the arm 16^a may be rocked against the outermost shoulder of the notch *b* and slide the bolt outwardly a distance sufficient to locate the notch *c* below the lower end of the detent-dog, which will drop by gravity into said notch *c*, whereupon the inner end of the locking-bolt 14 will have clearance from the tumbler-disk 7 and the opposite end of the locking-bolt 14 will be projected a proper distance out of the lock-casing, as shown in Fig. 3.

Assuming that the working parts of the lock are in locked condition, as indicated in Fig. 3, the index-fingers 25 may be arranged to indicate upon a preselected graduation of each scale 24, and the relative positions of the two groups of teeth 8 on the disk 7 may be positioned as represented in said figure. Furthermore, the teeth 23 on the tumbler-disks 21 22 may with advantage be positioned with regard to the teeth on the locking tumbler-disk 7, as shown in Figs. 3 and 4. When the bolt 14 is projected outward, as shown in Fig. 3, the tripping-lever 26 will be supported near its inner end upon the lower stud 27, free to slide when the disk 7 is rotated in the direction of the arrow *x* by engagement of the teeth 23 with the teeth 8. Preferably the teeth 23 on the disks 21 22, that are arranged to impinge, respectively, on the upper and lower groups of teeth 8, are of such length as will permit them to engage but a portion of their length therewith, and therefore give the locking-disk 7 a corresponding rocking movement in the direction of the arrow *x*.

To permit the retraction of the bolt 14, it is necessary to raise the detent-dog 17 out of the notch *c* and at the same time effect the rocking movement of the locking tumbler-disk in the direction of the arrow *x* sufficiently to dispose the notch 13 in said disk directly opposite the inner end of the locking-bolt, so that the bolt may be manually slid inwardly by means of the arm 16^a.

To effect the opening of the lock by removal of the obstacles to the manual sliding movement of the bolt 14 when the door is closed and locked, the knob 19^a is first turned a portion of a revolution in the direction of the arrow *x'*, so as to impinge the lowermost tooth 13^a

23 upon the uppermost tooth 8 and move the disk 7 a certain degree, indicated by the position of the index-finger 25 on the scale it is opposite, the tooth 23 leaving the tooth 8 it was engaged with. The lower knob 20^a is now turned in the direction of the arrow x^2 far enough to cause the lowermost tooth 23 on the lower disk 22 to engage with and give proper movement to the uppermost tooth 8 of the lower group of teeth on the disk 7.

The successive rotatable movement of the knobs 19^a 20^a, as explained, will have moved upward the middle tooth of the uppermost group of teeth 8 sufficiently to permit a tooth 15 on the upper disk 21 to engage said tooth and rock the disk 7 farther in the direction of the arrow x when the upper knob 19^a is turned in the direction of the arrow x' . The middle tooth 8 of the lower group of teeth on the 20 tumbler-disk 7 will now be raised into a position which will permit the second rotatable movement of the lower knob 20^a to impinge a tooth 23 on the tumbler-disk 22 against said middle tooth. The upper knob 19^a is now for 25 the third time moved in the direction of the arrow x' a predetermined distance, and following this partial rotation of the upper disk 21, that has been actuated by the knob 19^a, a final turning movement of proper degree is 30 communicated to the disk 22 by the manipulation of the lower knob 20^a. The successive partial rotations of proper degree given to the knobs 19^a 20^a and disks 21 22 they are 35 respectively connected to by the spindles 19 20 results in disposing the notch 13 directly opposite the inner end of the locking-bolt 14. It will also be seen that the step-by-step rocking movement of the tumbler-disk 7 in the direction of the arrow x , which raises the weight 40 11 into the position shown in Fig. 4, rocks the stud 28, that is above the lever 26, down upon said lever, that is rocked upon its pivot-support e upwardly at the end which contacts with the head 17^a of the detent-dog 17 and 45 elevates said dog, so as to remove it from the notch c simultaneously with the disposal of the notch 13 in alinement with the locking-bolt 14.

To unlock the lock when the parts are arranged as just explained, it is only necessary to manipulate the knob 16^b in the direction of the arrow y in Fig. 1, which will rock the arm 16^a against the innermost shoulder b' of the notch b , which will slide the bolt 14 so that it 55 enters and seats upon the bottom of the notch 13, which disposes the outer end of said bolt flush with the end wall 5^a of the lock-easing 5.

The varying degrees of successive rocking movements given to the tumbler-disks 21 22 60 are indicated by the graduations forming each scale 24, so that by noting these indices the combinations for unlocking the lock may be preserved for effecting such a purpose at any time.

It will be seen that when the lock is unlocked 65 it may remain so for any length of time, but may be locked by simply rocking the arm 16^a against the outer shoulder of the notch b , so as to slide the bolt 14 out of the notch 13, which will permit the weight 11 to 70 rock downward until the lowermost tooth 8 on the tumbler-disk 7 contacts with the stop-pin 12. The removal of the notch 13 from the inner end of the bolt 14 in an upward direction manifestly prevents the retraction 75 of the bolt 14, the relative disposal of the parts of the lock when locked in adjustment being shown in Fig. 3.

It is essential for the proper operation of the disks 7 21 22 that they should have proper 80 frictional contact with their pivot-supports, so as to prevent them from accidentally changing their positions when turned to lock the index-fingers upon a proper graduation, and it is preferred to envelop the stop-pin 12 85 with elastic material, so as to prevent noise when said pin is struck by the lower tooth 8 on the tumbler-disk 7.

Having thus described our invention, we claim as new and desire to secure by Letters 90 Patent—

1. In a lock, the combination with a casing, of a tumbler-disk pivoted at its center in the casing and notched in its periphery, said disk being weighted opposite the notch, two groups 95 of teeth on the periphery of the weighted disk, two rotatably-supported smaller tumbler-disks having teeth adapted to engage the teeth on the weighted disk, a slidably-supported bolt, means for manually sliding 100 said bolt toward and from the notch in the tumbler-disk, means for holding the bolt projected from the casing, and means, controlled by the tumbler-disks, for releasing the bolt.

2. In a lock, the combination with a casing, 105 of a tumbler-disk pivoted at its center in the casing, notched in its periphery and weighted near the edge opposite the notch, two groups of teeth spaced apart on the edge of the weighted disk, two rotatably-supported tumbler-disks in the casing, means for manipulating said disks, teeth on the smaller disks, adapted to engage with the teeth on the larger disk by the rotatable movement of said smaller disks, a slidably-supported locking-bolt 115 adapted to enter the notch when said bolt is manually moved, means for manipulating the bolt, means for holding the bolt projected from the casing, and means, controlled by the tumbler-disks, for releasing the 120 bolt.

3. In a lock of the character described, the combination with a casing, a main tumbler-disk and two smaller tumbler-disks, all pivoted in the casing, said smaller disks having 125 teeth that control the rotatable movement of the main disk, of a locking-bolt adapted to slide in the casing so as to enter a notch in

the main disk or be removed therefrom and projected out of the casing, means for manipulating the locking-bolt for its sliding movement, a detent-dog having a head and held to slide toward and from a notch in the locking-bolt, a tripping-lever pivoted in the casing and engaging one end with the head of the dog, the opposite end of the lever extending over the main tumbler-disk, and projections on the main disk, adapted to engage with the lever for its support and rocking movement.

In testimony whereof we have each signed

our names to this specification in the presence of two subscribing witnesses.
